STOVE

Clement Ehret, White Plains, N. Y.

Application May 21, 1935, Serial No. 22,511

19 Claims.

(Cl. 126—1)

This invention relates to stoves primarily intended for domestic use in the kitchens of homes, the invention being particularly, though not exclusively, directed to stoves utilizing gas, electricity or oil as fuel.

The primary object of the present invention is to improve upon stoves heretofore used to the end that they may be more convenient and satisfactory in the carrying out of their intended purposes and to the further end that they may more fully meet present day requirements of convenience, ease in cooking and safety in operation.

In my copending Patents Nos. 2,001,713 and 2,001,714, I have set forth various improvements and novel features in stove construction and the present invention serves to carry this advancement forward into further fields of improvement.

The present invention is directed to a stove of rotatable character, i. e., a stove wherein at least the top portion thereof on which the pots are supported over burners is rotatable, so that the housewife or cook, working at the stove, need not reach over an operating burner to inspect or remove a pot on the back portion of the stove with consequent danger of receiving a burn or catching fire from an adjacent burner. In conjunction with a stove of this general character, the present invention provides several important novel innovations. For example, there is associated with the stove a water supply and faucet, so placed with respect to the stove structure, that a pot resting upon the top of the stove may be replenished with water without requiring removal of the pot from the stove top and the stove and the water supply elements are interlocked mechanically in such manner that the water may be discharged from the faucet only when one of the burners of the stove, with which a pot may be juxtaposed, is in alignment or in proximity to the faucet. This feature thus provides for a water supply for pots on the stove, but at the same time insures alignment of the pots with respect to the faucet, so that water may not be inadvertently discharged directly on to the top of the stove between burners. While the discharge of water on the top of the stove might be serious when coal or gas is used as fuel, considerably more danger might well accompany the discharge of water on to an energized electric heating element.

A supplemental feature of the invention in this connection resides in the provision of a dual control for the water supply, one control being depending upon juxtaposition of the burner and the faucet, and the second control being of a manual

nature and being independent of the faucet, per se, or dependent upon movement of the faucet, as will hereinafter be more fully described.

A further feature of the water supply mechanism consists in the employment of a toggle arrangement associated with the faucet and which serves to enable raising and lowering of the stove top and corresponding adjustment of the faucet to appropriate heights.

Considerable research in connection with the problems of oven cooking, has disclosed that many accidents occur through the inability of cooks and housewives to properly see roasts, broils, etc., within the oven, it being the practice, when inspection is desired, to partially withdraw the food from the oven to permit of such inspection. This operation not infrequently results in spilling of hot fat upon the cook, burning of the hands, or dropping of the roasting pan or broiling grill upon the floor. It is manifest that, if proper inspection of the cooking food might be carried out without partially removing it from the oven, many of these dangers would be eliminated. To this end, the present invention provides that the oven or ovens have inspection windows which may be mounted in the doors or independently thereof, and there is used in conjunction with these inspection openings one or more sources of illumination preferably positioned exteriorly of the oven, but so arranged as to illuminate the interior of the oven when it is desired to carry out the inspection of the cooking foods therein without necessitating the opening of the oven door with consequent loss of heat and without subjecting the operator to the danger of injury. In conjunction with these inspection devices, the stove of the present invention embodies appropriate means for precluding such fogging of the inspection windows as would preclude proper visibility.

A further advance embodying the present invention consists of the employment of a novel arrangement and novel means whereby the stove body may be mounted for rotation, either in conjunction with an appropriate base or substantially upon the floor, together with or independently of novel mechanism for raising and lowering the stove body, so that the stove may be made convenient for either tall or short persons.

The present invention embodies other and additional features, which will be hereinafter more fully pointed out, in the annexed detailed description, shown in the accompanying drawings and set forth in the appended claims.

The accompanying drawings illustrate different

practical embodiments of the invention, but the constructions therein shown are to be understood as illustrative, only, and not as defining the limits of the invention.

5 Figure 1 is a side elevation of a stove embodying the present invention.

Figure 2 is a vertical section through the stove of Figure 1, this section being taken on the broken line 2-2 of Figure 3.

10 Figure 3 is a plan view of the stove top of Figures 1 and 2.

Figure 4 is a detailed central section of an oven door of the kind shown in the preceding figures.

15 Figure 5 shows a structure similar to that shown in the preceding figures, but with certain modifications in the water supply system.

Figure 6 is a section on the line 6-6 of Figure 5.

20 Referring first to Figs. 1-4, 1 designates a suitable hollow standard, shown as comprising a relatively broad base 2 surmounted by an upstanding cylindrical portion 3. The upper end of the cylinder 3 is open and projecting thereinto is a hollow plunger 4 mounted within the cylinder 3 for rotation and vertical adjustment. This vertical adjustment may be accomplished in various ways and by means of various types of mechanism, but, in these figures, the plunger 4 is threaded, as shown at 5, and cooperating with these threads is a hand wheel 6 having a threaded hub 7 screwed on to the plunger 4. In the under side of the hub 7 is formed a ball race and in the upper end of the cylinder wall is formed a complementary ball race and anti-friction bearings 8 are housed within these complementary ball races, so as to permit either rotation of the hand wheel 6 for the purpose of raising and lowering the plunger with respect to the standard when said 35 plunger is held against rotation.

40 It will be noted, however, that the friction between the hub and the cylinder because of the anti-friction means interposed between these two parts, is less than the friction between the hub and the plunger 4 and consequently normal rotation of the plunger may be accomplished without tending to change the vertical adjustment thereof, although, when the plunger is held against rotation, rotation of the hand wheel will effect such vertical adjustment without the application of undue power thereto. The upper end of the plunger is flanged at 9 and this flange is secured in any suitable way to the under side of the stove body which is indicated generally by 45 the reference character 10. The details of construction of the stove body may be of course varied within wide limits depending upon the type of fuel used and also upon the views of different stove designers and the present invention 50 is to be understood as not limited to these details other than as hereinafter specifically pointed out as important to this invention.

55 As shown, the stove body comprises an outer bottom 11, outer side walls 12, shown as cylindrical, and an outer upper oven wall 13. Spaced from these walls are inner oven walls comprising a bottom 14, side walls 15 and an upper side wall 16. The inside walls are spaced from the outside walls as is common in oven construction. A gas burner 17 is shown mounted beneath the inner bottom wall 14 and is supplied with gas 60 through a valve 18. The valve stem of this valve extends in opposite directions through the outside walls 12 and is provided exteriorly of said

latter walls with appropriate handles 19, whereby the valve 18 may be manipulated.

65 The inside oven walls are shown as provided with openings commonly found in stove construction for the circulation of heated gases and waste products of combustion and in addition thereto, there is provided in the outside oven walls and between the inner and outer top walls 13 and 16, outlet ports 19 which form part of the present invention. These outlet ports are for the exit 10 of heat and products of combustion to the flue and to provide for the carrying off of these gases, this invention includes a hollow manifold 20 positioned exteriorly of the outer wall 12 and embracing the same, being confined between flanges 15 21 which act as guides therefor. The mounting of this manifold 20, however, is such as to permit of relative rotation between the manifold and the stove body and flanges 21, so that the manifold may remain stationary, while the stove body rotates. One side of the manifold has a discharge outlet 22 connected with a flue or flue pipe 23 through a flexible connection 24 which has sufficient body to hold the manifold against appreciable rotation, but will nevertheless permit of raising and lowering of the stove body without destroying the connection between the manifold and the flue. The connection 24 is shown rather short in the drawings, but it may be made sufficiently long to allow of very considerable raising 30 and lowering movement and the manifold may be anchored against actual rotation, but for vertical movement with respect to the water pipe or other relatively stationary part.

70 The outer side wall 12 extends up beyond the outer top 13 for a sufficient distance to accommodate the burners 25 and supports above said burners a stove top 26 which may be in the form of a plate having any number of pot holes therein or may constitute a spider or may be of any other 40 suitable construction. As shown this plate is in the form of sheet metal or a flat casting having therein four holes 27, positioned immediately above four burners 25 and over each of these holes a cooking pot is adapted to be received. It 45 will be noted, however, that at the outer periphery of the top 26, there is provided an upstanding wall or border 28, characteristic of this invention and intended to preclude inadvertent dislodgment of pots or pans on the stove top, to keep drafts from blowing out the burners and to keep the heat in 50 contact with the pots.

75 Gas is fed to the several burners 25 through manually operable cocks 29 connected with a tubular ring 30 exteriorly of the stove body, as shown, and serving, in effect, as a hand wheel which may be conveniently grasped to rotate the stove body. This ring is supplied with gas through a pipe 31, forming a branch of a pipe 32 which feeds the valve 18 and which is arranged coaxially of the plunger and within the latter. This pipe 32 depends within the interior of the plunger and is connected to a main fuel supply pipe 33 by any suitable connection which will preclude the leakage of gas, but which will permit of rotation of the stove body and raising and lowering of the latter. An ordinary hose connection of a flexible character will suffice for this purpose, but, for illustrative purposes, the pipe 33 is shown as extending into the pipe 32, with an associated 60 packing gland or stuffing box 34 to preclude leakage. This arrangement permits of rotation and change in elevation of the stove body without interfering with the supply of fuel. The same 65 general arrangement may be used to supply oil, if 70

the stove is an oil burner and it will of course be understood that, in an electric stove, suitable wiring connections and heating elements will take the place of these gas connections and the burners.

5 In Figures 1 and 2, 35 designates a water supply pipe to supply a valve 36 within the base 2 and from this valve, a pipe 37 extends to a toggle and offset connection above the top of the stove body. The upstanding portion of the pipe 37 may 10 be stabilized or anchored in any suitable way, but, as shown, this is accomplished by a bracket 38 clamped about the standard and about the pipe 37. Incorporated in the pipe 37 immediately 15 above the bracket 38 is a valve 39. Both the valves 36 and 39 are of the normally closed type. They may be of any suitable make, wherein the valve is normally closed, but may be opened or unsealed by pressure applied to the valve stem. The valve stem 40 of the valve 30 is so positioned 20 as to project into the path of a series of cams 41 which cams are mounted or formed on the exterior of the stove body 10 in such positions as to engage with the valve stem 40 and open the valve 39 when any one of the four openings 25 27 of the stove top is juxtaposed to the faucet 42 which is fed with water through said valve 39. Mere rotation of the stove body into this position, however, will not supply water to the faucet 42 for the valve 36 remains closed. To supply water, 30 the valve 36 must be opened through depression of its valve stem 43. This may be accomplished in various ways manually, but for the purpose of illustration, I have shown a treadle 44 overlying the upper end of the valve stem 43 and pivoted at 45. This treadle may be normally elevated by the spring in the valve or may have an independent spring, but any convenient foot pressure on the treadle will depress the valve stem 43 and supply water to the faucet 42 in the event that 35 the faucet is juxtaposed with one of the burners. 40

By this interlocking of the parts, it will be apparent that in order to feed water to the faucet a burner must not only be in proper position, but the treadle must be manually operated. As pots 45 are set on a stove only over the burners, it therefore follows that when the water is turned on to discharge into a pot the parts will be in proper relative relation.

The faucet arrangement may vary from that 50 shown in Figs. 1 and 2, as hereinafter apparent, but, as shown, in these figures, the faucet 42 is connected to the upper end of the pipe 37 by an interposed pipe link 46. This pipe link cooperates with the faucet 42 after the manner of a toggle 55 and through appropriate pivotal connections with the faucet and with the pipe 37, so that toggle parts 42-46 may be manipulated to best suit the height of the individual pot into which water is to be discharged, the discharge taking place when 60 the pot is in proper position and the treadle operated manually.

The water supply in the structure of Fig. 5 varies somewhat from that shown in Figs. 1 and 2, in that the treadle control with the associated valve 36 is omitted in Fig. 5 and in lieu thereof the faucet 42 is connected directly with the upper end of the pipe 37 through a valve. The valve may be an ordinary one way plug valve, so formed that when the faucet is in the position 70 shown in dotted lines, the valve will open and water may flow through the faucet, whereas, when the faucet is in the full line position of this figure, the valve will be shut off. A suitable spring 75 47 serves to normally impel the faucet into a position to shut off the valve and hold it in this posi-

tion until the faucet is manually manipulated into the dotted line position to turn on the water, provided nevertheless that one of the cam members 41 has opened the valve 39, as hereinbefore described.

Any and all of the several embodiments of this invention may be provided with means to permit the inspection of foods in the oven and without opening the oven door. The oven or ovens may be provided with any number of doors 48, but I have shown in the drawings each oven as having two doors 48 positioned at diametrically opposite sides. Both doors are the same construction. Each comprises a suitable frame hinged to the stove body in any suitable manner, so that the doors may be opened and closed at will. The frame of each door, however, has a central opening 49 closed by a glass 50, as shown best in Figure 4, and this glass is preferably of heat resisting character, so as to serve as an inspection window and at the same time be well able to withstand the heat of the oven. Each door is moreover provided on its interior with a wiper 51 faced with steel wool, asbestos felt or other heat resisting material 52 bearing against the inner 20 face of the glass window 50 and mounted upon an arm 53 connected to the spindle of a handle 54 on the exterior of the door, so that through manipulation of this handle, fog, grease or the like may be wiped from the interior of the window 30 to render the same transparent.

Positioned between the doors and preferably on opposite sides of the stove body is appropriate illuminating means shown as embodying hinged housings 55. Each housing is positioned adjacent a port in the walls of the oven and the inner side of each port is closed by a transparent or translucent window 56 of appropriate material to stand the heat of the oven, such, for example, as pyrex glass. In each housing is mounted a lamp socket 57 adapted to receive an incandescent lamp 58, electric current to which is supplied through wires housed within conduits 59. These conduits lead to the interior of the hollow plunger 4 and additional conduits 60 lead to push buttons 61, one of which is positioned adjacent each oven door. The wiring connections are indicated diagrammatically in Figure 2, the wires 62 and 63 which feed this system being connected to brushes 64 and 65, respectively, mounted upon a ring of insulation 66 fixed on the interior of the plunger 4. An insulating disk 67 is supported on the lower end of the pipe 32 held loosely between collars 68 and 69 screwed on to said pipe, so that the insulating disk 67 is free to rotate but is raised 55 and lowered with the stove body. The outer periphery of this disk 67 has one or more projections which extend into vertical keyways 74 in the cylinder wall, so that while the disk is free to raise and lower with the stove body, it is kept 60 from rotating by the keyways 74.

On this insulating disk 67 is mounted two commutator rings 70 and 71 with which the brushes 64 and 65 respectively contact at all times and these commutator rings are fed by wires 72 which 65 form parts of a feed cable 73 looped within the hollow base to permit of raising and lowering movement of the stove body while permitting uninterrupted feed of current to the wires 62 and 63.

When a person desires to inspect the contents 70 of the oven, one of the push buttons 61 may be pressed to energize the stove lamps 58 and illuminate the entire interior of the oven and if the window 50 be clouded, the wiper may be operated to permit of clear vision. These operations may 75

be carried out without opening the oven door and permitting the loss or waste of heat and without danger to the operator. The sources of illumination may be placed otherwise than specified, but 5 the showing of the drawings is not only convenient, but thoroughly efficient. The advantage of placing the lamps 58 in housings hinged to the stove body is that these housings may be open at any time for replacement of lamps, and while the 10 lamps are thus positioned to properly illuminate the interior of the oven, they are removed from the direct heat of the latter. If desired, the housings 55 may be ventilated by perforations or holes, although this is not essential and the panels 56 15 may also be equipped with wipers similar to those on the doors.

The foregoing detailed description sets forth various forms of the present invention, as illustrative, but it is to be understood that the invention 20 is not restricted to details of construction which may be modified within the scope of the appended claims.

Having thus fully described the invention, what I claim as new and desire to secure by Letters 25 Patent is:

1. A stove comprising a stove body mounted for rotation and having a plurality of fuel burners, a water supply duct having a water outlet positioned to deliver water into receptacles associated 30 with the burners, a valve for controlling the flow of water through said duct, and means rotatable with the stove body for controlling said valve.

2. A stove comprising a stove body mounted for rotation and having a plurality of fuel burners, a 35 water supply duct having a water outlet positioned to deliver water into receptacles associated with the burners, a valve for controlling the flow of water through said duct, and valve operating devices movable with the stove body to open said 40 valve when one of the burners is juxtaposed with the water outlet.

3. A stove comprising a stove body mounted for rotation and having a plurality of fuel burners, a water supply duct having a water outlet positioned to deliver water into receptacles associated 45 with the burners, a valve for controlling the flow of water through said duct, and valve operating devices movable with the stove body to open said valve when one of the burners is juxtaposed with the water outlet, and an additional manually operable valve included in the duct to control the 50 flow of water through the duct when the other valve is open.

4. A stove comprising a stove body mounted to 55 rotate and adapted to support pots for cooking, a water supply duct having an outlet positioned to discharge water into pots thus supported, a controlling valve in said duct, and means rotatable with the stove body to control the opening 60 and closing of the valve in accordance with the angular position of the stove body.

5. A stove comprising a body mounted to rotate and adapted to support cooking pots, a water supply duct having an outlet positioned to discharge 65 water into a pot thus supported, a normally closed valve in said duct, and means rotatable with the stove body to engage with and open the valve when the stove body is in predetermined angular positions of its rotary movement.

6. A stove comprising a body mounted to rotate and adapted to support cooking pots, a water supply duct having an outlet positioned to discharge water into a pot thus supported, a normally closed valve in said duct, and means rotatable 70 with the stove body to engage with and open

the valve when the stove body is in predetermined angular positions of its rotary movement, and an additional manually operable valve in said duct to permit the flow of water through the duct when the other valve is opened. 5

7. A stove comprising a body mounted to rotate and adapted to support cooking pots, a water supply duct having an outlet positioned to discharge water into a pot thus supported, a normally closed valve in said duct, means rotatable with the stove 10 body to engage with and open the valve when the stove body is in predetermined angular positions of its rotary movement, an additional manually operable valve in said duct to permit the flow of water through the duct when the other valve is opened, the water outlet of the duct being pivotally mounted with respect to the remainder of the duct and the manually operable valve being operatively connected to and operated by the pivotal movement of said water outlet. 15

8. A stove comprising a stove body mounted to rotate and adapted to support pots for cooking, a water supply duct having an outlet positioned to discharge water from the duct into a pot thus supported, an automatic valve included in said 20 duct, means rotatable with the stove body to operate said valve, and a manually operable valve also included in said duct.

9. A stove comprising a stove body mounted to rotate and adapted to support pots for cooking, a water supply duct having an outlet positioned to discharge water from the duct into a pot thus supported, an automatic valve included in said 25 duct, means rotatable with the stove body to operate said valve, a manually operable valve also included in said duct, and a manually operable treadle for controlling the latter valve. 35

10. A stove comprising a base, a stove body mounted for rotation on the base and adapted to support a cooking vessel, a water duct supported 40 by the base and having an outlet positioned to discharge the water into such cooking vessel, and valvular means controlled by the stove body to limit the supply of water to the outlet to predetermined angular positions of rotary movement of the stove body. 45

11. A stove comprising a base, a stove body mounted on the base for rotation and vertical adjustment with respect to the latter, said stove body being adapted to support a pot for cooking, 50 a water supply duct provided with a vertically extensible outlet to discharge water into a juxtaposed pot supported on the stove body, a valve in said duct, and means rotatable with the stove body to open said valve when said stove body is 55 in a predetermined angular position of its rotation.

12. A stove comprising a stove body, means for supporting the stove body for independent vertical and rotatable adjustment, a water supply duct provided with a vertically extensible outlet positioned to discharge water into a cooking pot supported in juxtaposed relation on the stove body, a valve in said duct, and means, rotatable with the stove body, to open said valve 65 when the stove body is in a predetermined angular position of its rotation.

13. A stove comprising a stove body mounted for independent vertical and rotatable adjustment, a water supply duct provided with a water outlet positioned to discharge water into a cooking pot supported on the stove body, a valve in said duct, and valve operating means, controlled by the position of the stove body, to open the valve when the stove body is in pre- 70 75

determined, angular positions of its rotation.

14. A stove comprising a stove body mounted to rotate and adapted to support pots for cooking, a water supply duct having an outlet positioned to discharge water into pots thus supported, a valve in said duct, and valve operating means, controlled by the position of the stove body, to control the opening and closing of the valve in accordance with the angular position of the stove body.

15. A stove comprising a stove body mounted for independent vertical and rotatable adjustment and adapted to support pots for cooking, a water supply duct having an outlet positioned to discharge water into pots thus supported, a valve in said duct, and valve operating means, controlled by the position of the stove body, to control the opening and closing of the valve in accordance with the angular position of the stove body.

16. A stove comprising a vertically adjustable stove body mounted to rotate and adapted to support pots for cooking, a water supply duct having an outlet positioned to discharge water into pots thus supported, a valve in said duct, and valve operating means, controlled by the position of the stove body, to control the opening and closing of the valve in accordance with the angular position of the stove body, said water supply duct being vertically extensible to compensate for vertical adjustment of the stove body.

17. A stove comprising a stove body mounted for vertical movement and adapted to support a cooking vessel, and a water supply duct having

an outlet positioned to discharge water into a vessel thus supported, said water supply duct being vertically extensible to compensate for vertical movement of the stove body.

18. A stove comprising a stove body mounted for rotation and adapted to support a cooking vessel, a water supply duct in proximity to the stove body and having an outlet section to deliver water into a vessel thus supported, said outlet section having an adjustable connection with the remainder of the supply duct, a valve included in said adjustable connection and arranged to open when said outlet section is positioned to discharge water into such vessel, and means for normally retracting said outlet section and closing the valve.

19. A stove comprising a stove body mounted for rotation and adapted to support a cooking vessel, a water supply duct in proximity to the stove body and having an outlet section to deliver water into a vessel thus supported, said outlet section having an adjustable connection with the remainder of the supply duct, a valve included in said adjustable connection and arranged to open when said outlet section is positioned to discharge water into such vessel, means for normally retracting said outlet section and closing the valve, an additional valve in said duct, and means, controlled by the stove body, for opening the latter valve when the stove body is in predetermined angular positions of its rotation.

CLEMENT EHRET.
